DEODORANT CONTAINER FOR TOILET BOWLS

Filed May 29, 1931

FIG 1

FIG 2

UNITED STATES PATENT OFFICE

WALTER S. DUWELIUS, OF CINCINNATI, OHIO, ASSIGNOR TO MARY E. FORCHHEIMER, OF CINCINNATI, OHIO

DEODORANT CONTAINER FOR TOILET BOWLS

Application filed May 29, 1931. Serial No. 541,005.

This invention relates to certain improvements in the use of deodorants for toilet bowls and has relation more particularly as an attachment therefor; and the object of 5 the invention is to provide a device of this general character wherein is afforded an effective means for maintaining a deodorant container under the flushing rim of a toilet bowl without adjustment and in a manner of 10 easy access for replenishing the deodorant.

The invention consists in the details of construction and in the combination and arrangement of the several parts of my improved deodorant container for toilet bowls, 15 wherein certain important advantages are attained and the device is rendered simpler, less expensive and otherwise more convenient and advantageous for use.

I attain these objects by the formations illustrated in the accompanying drawing, in which,

Figure 1 shows a vertical front view of the container; Figure 2 is a detailed view in perspective, of the container showing its position when attached to the flushing rim of a toilet bowl. Similar numerals refer to similar parts throughout the two views.

Numeral 1 is a cross-section of a flushing rim of a toilet bowl; 2 is a formation of spring wire, of which 3—3 are clamp members; 4 is a three-sided, one piece receptacle having loose fitting ends and perforations to receive eyelets 6; 5 is a strap.

The assembled construction consists of the 35 wire formation 2 fastened to the receptacle 4 by means of strap 5 and eyelets 6, or other suitable means, in such position that when the device is clamped to the flushing rim of a toilet bowl, the receptacle will be held under 40 and against the bottom of the flushing rim of the toilet bowl by the wire formation.

A novel feature of the invention is the manner in which the device is attached to the toilet bowl rim. This is accomplished by 45 compressing the clamps 3—3 toward each other, in which position, the distance between points 7—7 of the wire formation and the top of the receptacle 8—8, is at its maximum and permits points 7—7 of the wire formation to pass over the top of the toilet bowl

rim and permits the top of the receptacle 8—8 to pass under the toilet bowl rim, so that when the tension on clamps 3—3 is released, the lateral expansion of the clamps draws the receptacle up under the rim of the toilet bowl 55 and holds the device in position by pressure on top and bottom of the rim of the toilet bowl.

With the device thus in position and containing a deodorizing compound compressed 60 into a block to fit the receptacle, the deodorizing material, being so compounded as to form a gas heavier than air, the gas, so formed, remains in the toilet bowl until, dissipated by flushing, it becomes mixed with other 65 odors and destroys or neutralizes them.

I claim:

A deodorant container for use in a toilet bowl comprising a receptacle having a bottom and side walls for receiving a block of 70 deodorant material, means for mounting said receptacle within the space formed by the inner overhang of the rim of a toilet bowl comprising a pair of spring wires secured to the receptacle, said wires extending upwardly along the outer side of the receptacle and then outwardly and upwardly in arcs converging in opposite directions, said wires being then bent to extend parallel and then having downwardly bent ends also extending 75 parallel whereby clamping arms are formed by the bent ends, which, when the first noted parallel portions are pressed together, release the clamping engagement of the downwardly bent ends from engagement with the outer 80 surface of the bowl rim, whereby the container may then be removed and replaced on the bowl rim for the replacement of the material within the receptacle.
